PACKAGE WITH INDIVIDUAL POCKETS
FOR PADS

Eli A. Zackheim, Princeton, N.J., assignor to Johnson & Johnson, a corporation of New Jersey
Filed May 9, 1963, Ser. No. 279,057
5 Claims. (Cl. 206—63.2)

The present invention relates to medicated pads for application to the skin, more particularly to such pads which are in the form of relatively small pieces most suitably stamped or cut from a layer of sheet material, and to a novel package therefor and a method of manufacturing this package.

According to this invention, a plurality of pads are assembled with other sheet material to form a single laminated package in which the pads may be enclosed in sterile condition in individual pockets. The individual pads remain in place in the product sheet from which they are stamped or cut and this product sheet becomes part of the package laminate. The laminate comprises a relatively heavy backing sheet, a cover sheet, and the product sheet; and the sheets are assembled with the product sheet sandwiched between the backing sheet and the cover sheet. The product sheet is adhered to the backing sheet, on one side, and the cover sheet, on the other side, in areas completely surrounding the pads to form a plurality of sealed individual pockets enclosing the pads. The backing sheet at each of the pockets is scored or grooved from the outside of, and partially through, the backing sheet along a breaking line crossing the pocket, and the laminate is cut from the breaking line to the nearest edge of the laminate on each side of each pocket; thereby forming a tab adapted to be separated or detached easily from the package by tearing the backing sheet and the cover sheet along the breaking line. Separation of one of the tabs from the package opens one of the pockets and exposes the pad it contains without disturbing the integrity of the remainder of the package.

In a preferred embodiment of this invention, the individual pads are impregnated with a hemostatic agent and the pads are intended for use during shaving to stop the flow of blood and help heal any cuts which may occur. In this case, it is important that a pad be immediately available when needed but that the remainder of the pads in the package be maintained free of contamination from blood, soap, and other foreign materials. It is an important feature of the package of this invention that each of the tabs may be detached easily to expose a hemostatic pad when needed. As will be explained more fully hereinafter, the tab may be detached in such a way that the pad remains in the tab with its end protruding therefrom, or the pad may be left protruding from that portion of the pocket which remains with the package after the tab is detached. While there are certain advantages to either of these techniques, in either case, the pad, itself, is readily available for use.

Another important advantage of the package of this invention is that it is adapted to be sterilized quickly in a carboxide autoclave. The various parts are designed to be assembled in such a way that sterilizing gases may penetrate readily into the individual pockets of the completed package and thereby completely sterilize its contents.

It also is preferred that the cover sheet be transparent so that the pads are visible in the pockets from one side of the package. For instance a colored hemostatic agent may be applied to the visible pad faces so as to bring them sharply into view and make them clearly visible to the consumer.

The method of this invention, wherein the individual

2

pads remain in place in the product sheet from which they are cut and the product sheet becomes part of the package laminate, also is highly advantageous because it facilitates the definite positioning of the pads in the package in accordance with the arrangement in which they are cut from the product sheet and also facilitates the formation of the sealed pockets enclosing the pads. The pads are either cut from the product sheet after it is applied to the backing sheet, in which case they may be completely cut; or they are at least partially cut from the product sheet prior to the application of the product sheet containing the pads to the backing sheet. Normally, in the latter case, the pads are almost completely cut from the product sheet except for short nibs 15 on opposite sides of the pads which hold the pads in position. The nibs also may be used when the pads are cut after application of the product sheet to the backing sheet for convenience in retaining the pads in position and to insure sterility as will be explained more 20 fully hereinafter.

Other and further advantages of this invention will be apparent from the following description and claims taken together with the drawings wherein:

FIG. 1 is a view in perspective of a backing sheet of 25 a package in accordance with one embodiment of this invention;

FIG. 2 is a view of the same backing sheet after it has been coated with a plastic film;

FIG. 3 is a view in perspective of a product sheet 30 according to this invention superimposed over the backing sheet of FIG. 2;

FIG. 4 is a partially broken away view of portions of the sheets of FIG. 3 after the product sheet has been adhered to the backing sheet;

FIG. 5 is an enlarged sectional view taken along the line 5—5 of FIG. 4;

FIG. 6 is a view in perspective of a smaller fragment of the sheets of FIG. 4 after the pads have been cut from the product sheet;

FIG. 7 is an enlarged view partly in section and partly in elevation taken along the lines 7—7 of FIG. 6;

FIG. 8 is an enlarged sectional view along the line 8—8 of FIG. 6;

FIG. 9 is a view in perspective of the assembled sheets 45 of FIGS. 3 and 4 with a cover sheet positioned above them;

FIG. 10 is a view of a fragment of the sheets of FIG. 9 after the cover sheet has been adhered to the product sheet in areas surrounding the pads to form a laminate 50 comprising pockets for the pads;

FIG. 11 is a view in perspective of the sheets of FIG. 10 with the laminate inverted, showing the scoring and die cutting of the laminate;

FIG. 12 is a view in perspective of a fragment of the 55 laminate of FIG. 11 in an upright or noninverted, position;

FIG. 13 is an enlarged sectional view along the line 13—13 of FIG. 12;

FIG. 14 is an inverted enlarged sectional view taken 60 along the line 14—14 of FIG. 11;

FIG. 15 is an enlarged sectional view taken along the line 15—15 of FIG. 12;

FIG. 16 is a view in perspective showing one of the tabs being removed from the package laminate;

FIG. 17 is a fragmentary view in perspective which 65 also shows removal of a tab from the package of this invention;

FIG. 18 is a smaller fragmentary view in perspective showing the tab being removed with the pad in place in the tab;

FIG. 19 is another perspective view of the pad in place in the tab;

FIG. 20 is a view in perspective showing another technique for removing a tab according to this invention wherein the pad is retained in the package after the tab is removed;

FIG. 21 is a fragmentary view in perspective showing a portion of a backing sheet according to a slightly different embodiment of this invention wherein a laminating adhesive is applied in a pattern defining the pockets;

FIG. 22 is a view in perspective showing a product sheet wherein the pads have been partially cut from the sheet and together with the sheet are positioned above the backing sheet of FIG. 21;

FIG. 23 is a fragmentary view in perspective showing the sealing of the product sheet to the backing sheet;

FIG. 24 is a fragmentary view in perspective showing the positioning of the cover sheet over the laminated sheets of FIG. 23;

FIG. 25 is another fragmentary view in perspective showing the sheets of FIG. 24 after they have been adhered to one another to form pockets surrounding the pads;

FIG. 26 is a view similar to FIG. 11 showing the laminate inverted for the purpose of illustrating the cutting and scoring thereof;

FIG. 27 is an enlarged sectional view similar to FIG. 13 but taken through the embodiment of FIGS. 21-28;

FIG. 28 is an enlarged sectional view similar to FIG. 14, but also of the embodiment of FIGS. 21-28.

Referring particularly to FIGS. 1-15 of the drawings, there is shown a package according to a preferred embodiment of the invention and a method of manufacturing it. FIG. 1 illustrates a backing sheet 31 which is relatively heavy compared with the cover for the package and normally considerably heavier than the product sheet from which the pads are cut. Typically, a die-cut 30 bleached sulfate paper board about 0.015-0.020 inch thick may be used for this purpose. A small hole 32 is punched adjacent one of the edges of the sheet for hanging the package on a rod for storage or display purposes. In FIG. 2, a thin laminating film 33 of a thermoplastic material such as saran, polypropylene, or linear polyethylene, is applied to the top surface of the backing sheet 31 in the area where the backing sheet and the product sheet are to contact one another. This film 33 may be only a fraction of a mil in thickness but is substantially continuous as applied to the backing sheet. FIG. 3 illustrates a product sheet 34 in position above the coated portion of the backing sheet 31. The outlines of the pads to be cut from the product sheet are already defined by medication 35 applied to the product sheet in the shape of the pads. The product sheet 34 is formed from material which is absorbent enough to contain the medication 35 and absorb blood or any other fluid for which it is intended, and yet firm, or stiff, enough to give the individual pads sufficient rigidity, or body, for use. When the pads are intended for hemostatic purposes in connection with shaving, as described briefly hereinbefore, the product sheet may be cut from a Whatman #3 filter paper in the neighborhood of 0.010-0.015 inch thick. This filter paper is relatively porous as compared with the backing sheet. The hemostatic agent may be applied to the top surface of the product sheet in the outline of the pads by silk screening, gravure printing, impregnation or the like.

FIGS. 4 and 5 illustrate the heat sealing of the product sheet to the backing sheet. A heat sealing die, or shoe, is used to apply heat to the laminate of the product sheet and the backing sheet in a pattern which establishes a heat sealing area 36 surrounding the individual pads. Thus, the product sheet is sealed to the back sheet only in the areas surrounding the pads to be cut from the product sheet.

FIG. 6 illustrates the laminate of FIG. 4 after pads 37 have been cut from the product sheet 34. A die is used for this purpose which almost completely cuts the pads from

the product sheet, but leaves a pair of short nibs 38, along the center line A-B in FIG. 6, for retaining the pads in position. It should be noted that the shape of the pads 37, as cut, is the same as the pattern in which the medication 35 or hemostatic agent originally was applied to the product sheet. The application pattern for the medication need not be the same as the shape of the pads although it must apply sufficient medication to the pads in the right locations.

FIG. 7 is a sectional view taken along one edge of one of the pads 37 and illustrates one of the nibs 38 referred to above. These nibs 38 are located along the line A-B which represents one of the lines along which the backing sheet will be scored to provide a breaking line for removal of tabs from the package, as will be described more fully hereinafter.

Both FIGS. 7 and 8 also show that when the pads 37 are cut from the product sheet 34, the dies also cut through the laminating film 33 and penetrate the backing sheet 31 slightly. Thus, cuts 30 are formed in the laminating film 33 in the outline of the pads 37. These cuts 30 are for the purpose of facilitating sterilization of the interior of the package through the backing sheet 31. When ethylene oxide or steam is used for sterilization in an ordinary production sterilization cycle of one-half to one hour, the thermoplastic laminating film 33 might provide a barrier to penetration of the sterilizing gas through the backing sheet if it were not for the above-referred-to cuts.

FIG. 9 shows a cover sheet 41, which preferably is transparent, in position over the product sheet 34, and FIG. 10 illustrates a portion of the package after the cover sheet 41 has been adhered to the product sheet in the sealing area 36 surrounding the pads to form the package laminate. Preferably, the cover sheet 36 is a material which may be heat sealed to the product sheet 34. For instance, a linear polyethylene film about one mil or less in thickness may be used for this purpose, or a laminate of glassine and vinylite may be employed. In the latter case, the vinylite, besides being heat sealable, should also be heat sterilizable, i.e., capable of retaining its integrity and its seal at temperatures in the neighborhood of 250° F. A glassine vinylite laminate wherein about 25 pounds per ream of glassine and 5-10 pounds per ream of vinylite are employed, is suitable for this purpose. It should be noted that the cover sheet may be sealed to the product sheet in the same pattern as the product sheet is sealed to the backing sheet. However, while this is convenient, it is not necessary. When the cover sheet 41 is sealed to the product sheet 34, pockets 42 enclosing the pads 37 are completed. Sufficient clearance is allowed between the edges of the pockets 42 and the pads 37 to allow the pads to be removed readily therefrom when desired.

The laminated package according to this embodiment is completed, as shown in FIG. 11, by inverting the sheets of FIG. 10 and die cutting and scoring the laminate to form a tab 43 for each of the pads 37 and its corresponding pocket 42. The backing sheet 31 is scored from its bottom surface part way through its thickness to form two breaking lines or grooves 44. Each of the breaking grooves 44 runs through a row of the pads 37 and their corresponding pockets 42 in such a way as to cross the pockets at the point where it is desired to open them. The laminate is cut from each of the breaking grooves 44 to the nearest edge of the laminate on each side of each of the pockets 42 to form tabs 43 which are individually separable from the remainder of the package by breaking the backing sheet and the cover sheet along the appropriate breaking groove 44. The corners 45 of the tabs 43 are beveled at the ends of the tabs during the die cutting, as shown most clearly in FIGS. 11 and 12 for convenience in gripping and removing the tabs 43.

FIGS. 12-15 illustrate portions of the completed lami-

nated package according to this embodiment of the invention. It will be seen that the medicated pads 37 remain in position in the product sheet 34 and are enclosed in sealed pockets 42 formed by the backing sheet 31, the product sheet 34, and the cover sheet 41. These pockets 42, when sterilized, remain sterile and protect the pads 37 from airborne bacteria and other contamination. However, the package is so designed that the pockets 42 are penetrable by sterilizing gases under pressure. The penetration of sterilizing gases into the pockets through the 10 backing sheet 31 and the cuts 30 in the thermoplastic film 33 applied to the sheet has been described hereinbefore. As mentioned previously, the nibs 38, shown most clearly in FIGS. 6 and 7, have an important secondary function of assuring the sterility of the pockets 42. A quick glance at FIG. 14 will show that the breaking grooves 44 in the backing sheet might contact the cuts 30 made in the backing sheet 31 through the laminating film 33 in the outline of the pads where the grooves 44 would cross these cuts, if it were not for the nibs 38. Thus, one of the grooves 15 44 is shown dotted in FIG. 7 and crossing under the pads 37 through the nibs 38 so as to avoid the possibility of joining the cuts 30.

FIGS. 16-20 illustrate two ways in which the laminated package of this invention may be used. As mentioned hereinbefore, the individual tabs 43 may be detached from the package in such a way that the pad 37 remains in the tab 43 and is removed from the package with the tab as the tab is detached by tearing the package along the breaking groove 44. In this case, the pad 37 is held in the tab 43 by the fingers gripping the tab, as shown in FIG. 16, and the other end of the pad 37 protrudes from the tab 43 after it has been removed from the package, as shown in FIGS. 18 and 19. The tab 43 then may be used as a holder for applying the pad 37 to a cut or the like.

On the other hand, it may be desirable to leave the pad 37 in position in the package after the tab is removed therefrom, as shown in FIG. 20. To accomplish this, the hand gripping the package also is applied to one end of the pad 37 and the tab 43 is gripped by the other hand in such a way as not to contact the opposite end of the pad. One advantage of this technique may be that it leaves the exposed pad 37 free to be removed easily from the package and applied directly to a cut. In both of the above-described cases the tab 43 may be removed easily from the package by tearing along the breaking groove or line 44 without disturbing the integrity of the remainder of the package, or in the case of a sterile package, without interfering with the sterility of the remainder of the package.

FIGS. 21-28 illustrate a package according to a somewhat different embodiment of the invention and a method of manufacturing this package. The materials used are the same as, or similar to, those described in connection with FIGS. 1-15, unless otherwise stated. FIG. 21 illustrates the application of a laminating adhesive 51 to the backing sheet 31 in a pattern. This pattern corresponds to the pattern in which it is intended to seal the product sheet to the backing sheet. FIG. 22 shows a product sheet 52 superimposed above the adhesive area of the backing sheet. A plurality of pads 53 are already cut from the product sheet but are retained in position therein by a pair of short nibs 54 connecting each of the pads 53 with the sheet 52. These nibs 54 are easily broken when it is desired to remove the pads from the package. FIG. 23 illustrates the positioning of the product sheet 52 containing the pads 53 on the backing sheet with the pads located within the adhesive-free areas of the backing sheet. The backing sheet 31 is adhered to the product sheet 52 through the laminating adhesive 51 by the application of heat and/or pressure to the two sheets. FIGS. 24 and 25 illustrate the application of a transparent cover sheet 55 over the product sheet to complete pockets 56 enclosing the pads. Again, the cover sheet 55 may be sealed to the backing sheet 31 by applying heat and pressure through the cover sheet 55 in areas surrounding the 75

pads 53 but spaced therefrom sufficiently to define clearance between the edges of the pads and the edges of the pockets. FIG. 26 is similar to FIG. 11 and also illustrates the way in which the laminated sheets are die cut and scored to form tabs 57 by inverting the laminate and cutting through the bottom of the backing sheet.

As mentioned hereinbefore, FIGS. 27 and 28 are similar to FIGS. 13 and 14, and illustrate this embodiment of the invention in the same way as FIGS. 13 and 14 illustrate the embodiment of FIGS. 1-15. As shown in FIGS. 27 and 28, in this embodiment of the invention, there is no laminating film under the pads 53. Thus, sterilizing gases may pass directly through the backing sheet 31 into the pockets 56 enclosing the pads 53 and it is not necessary to cut into the backing sheet in the outline of the pads, as in the embodiment of FIGS. 1-15. This allows the pads to be cut from the product sheet prior to assembly of the product sheet with the backing sheet, as described above.

As described in connection with FIGS. 1-15, the pads 53 are enclosed in individual pockets 56 formed by the backing sheet 31, the product sheet 52, and the cover sheet 55, and may be removed easily from these pockets by either of the techniques described in connection with FIGS. 16-20, merely by tearing one of the tabs 57 from the remainder of the package. Again, removal of one of the tabs, only opens one of the pockets and provides access to one of the pads, and does not disturb the integrity or the sterility of the remainder of the package.

A still different preferred embodiment of this invention is in the nature of an improvement over and a combination of certain of the features of each of the foregoing embodiments. Referring particularly to FIGS. 1-15, after the heat sealable laminating film 33 is applied to the backing sheet 31, sterilizing cuts, not shown, are made through the film 33 approximately where each of the pads 37 will cover the film in such a way that the cuts enter each of the pockets 42. The sterilizing cuts are carefully located so that they will not strike the breaking grooves 44 in the bottom of the backing sheet 31 and therefore allow airborne bacteria and other contamination to pass into the pockets through the breaking grooves 44 and the sterilizing cuts. Nevertheless the cuts do allow penetration of sterilizing gases under pressure into the pockets 42 through the backing sheet 31 and then through the sterilizing cuts, themselves. Next the product sheet 34, which in this embodiment is like the product sheet 52 because the pads are already partially cut from the product sheet, is placed in position over the heat sealable film 33 and the cover sheet 41 is positioned over the product sheet. When the sheets are in position all three sheets are sealed together to form a laminate with the product sheet 34 between the backing sheet 31 and the cover sheet 41. A heat sealing die or shoe is used which applies heat and pressure to the laminate in the sealing pattern shown in FIG. 4 to seal one face of the product sheet 34 to the backing sheet 31 and the other face of the product sheet to the cover sheet 41 in areas completely surrounding said pads without adhering the pads to backing sheet or the cover sheet. The product and the method of this embodiment are in every other respect the same as those of FIGS. 1-15. The chief advantage of this embodiment is in its simplicity and the elimination of the need for precise registration as between the nibs 38 and the grooves 44, or the need for applying the laminating adhesive or film to the backing sheet in a careful pattern as described in connection with the embodiment of FIGS. 21-28.

Having now described the invention in specific detail and exemplified the manner in which it may be carried into practice, it will be readily apparent to those skilled in the art that innumerable variations, applications, modifications, and extensions of the basic principles involved may be made without departing from its spirit or scope.

The invention claimed is:

1. A package with individual pockets for pads of sheet

material comprising a product sheet portion and coextensive portions of a relatively heavy backing sheet and a cover sheet, said product sheet portion being sandwiched between the coextensive portions of the backing sheet and the cover sheet to form a laminate, said product sheet portion comprising a plurality of pads at least partially cut from the product sheet portion and remaining in position therein, said product sheet portion in an area completely surrounding said pads being adhered one side to the backing sheet and the other side to the cover sheet, but loose from said backing sheet and said cover sheet throughout the areas of said pads to form a plurality of sealed pockets enclosing said pads, said backing sheet at the individual pockets being scored from the outside of and partially through the backing sheet along a breaking line crossing the pockets, and said laminate being cut from the breaking line to the nearest edge of the laminate on each side of the individual pockets to form a tab separable from the remainder of the package by tearing the backing sheet and the cover sheet along the breaking line to open the pocket and expose the pad it contains. 15

2. A package for pads of sheet material according to claim 1, wherein the pads are completely cut from the product sheet except for short nibs connecting the pads with the sheet. 20

5

10

25

3. A package for pads of sheet material according to claim 1, wherein medication is applied to at least one surface of the pads and the interiors of the pockets are sterilized to provide a sterile sealed package.

4. A package for pads of sheet material according to claim 1, wherein the pads are formed of absorbent and firm sheet material and a hemostatic agent is applied to at least one surface of the pads.

5. A package for pads of sheet material according to claim 1, wherein the cover sheet is transparent and forms the top of the pockets and the pads are visible through the cover sheet when in position in the pockets.
